UNITED STATES PATENT OFFICE.

ALEXANDER M. KELLY, OF KNOXVILLE, AND BENTON L. SHANER, OF PITTSBURGH, PENNSYLVANIA.

TWINE-HOLDER.

1,131,843.

Specification of Letters Patent. Patented Mar. 16, 1915.

Application filed January 23, 1914. Serial No. 313,901.

To all whom it may concern:

Be it known that we, ALEXANDER M. KELLY and BENTON L. SHANER, citizens of the United States, residing, respectively, at 5 Knoxville and at Pittsburgh, in the county of Allegheny and State of Pennsylvania, have invented a new and useful Improvement in Twine-Holders, of which the following is a full, clear, and exact description, reference being had to the accompanying drawings, forming part of this specification, in which—

Figure 1 is a view partly in side elevation and partly in section of a twine holder embodying our invention; Figs. 2 and 3 are end views with the cap removed from the drum and showing the parts in different positions; Fig. 4 is an end view of the supporting bracket; Fig. 5 is a detail sectional view showing a portion of the shaft and of a twine-holding quill.

Our invention has relation to twine holders, and is designed to provide a simple, efficient and convenient form of twine holder which can be manufactured and sold at a relatively low cost; which can be used in a variety of different positions; and which will automatically wind up any excess cord or twine which may be pulled off 30 from the spool, the winding action being effective so long as any cord remains on the spool.

The nature of our invention will be best understood by reference to the accompanying drawings, in which we have shown the preferred embodiment thereof and which will now be described, it being premised, however, that various changes can be made in the details of construction and arrangement of the parts, without departing from the spirit and scope of our invention, as defined in the appended claims.

In these drawings, the numeral 2 designates a central longitudinal shaft, upon 45 which the spool of cord or twine is slipped. This spool is indicated at A in dotted lines in the drawings, being wound upon the usual quill B. The shaft is preferably of wood for the sake of cheapness having its 50 ends provided with metal ferrules 3, carrying the squared projections 4, which are designed to rest in squared seats in a supporting bracket and thus hold the shaft against

rotation. The supporting bracket which we have illustrated consists of a single piece 55 of sheet metal having its end portions bent, as shown at 5, to provide parallel supporting arms for the shaft 2. In order to provide for the use of the twine holder in different positions, each of the supporting 60 arms 5 is shown as having a cruciform slot therein, consisting of the four arms 6, 7, 8 and 9, the slot 9, opening out through one side of the arm. When the twine holder is used in the upright position shown in 65 Fig. 1, the squared projections 4 of the shaft 2 will rest in the portions 8 of the slots. When the device is used in the horizontal position, said projections will rest in the portions 7 of the slots, and when the device 70 is used in an inverted suspended position, said projections will rest in the portions 6 of the slots.

The numeral 10 designates a cylindrical drum which is mounted to rotate on the end 75 portions of the shaft 2. This drum is shown as formed of a sheet metal body having cut therein a plurality of symmetrical spaced openings 11, extending longitudinally thereof, with cap members 12 fitted over the end 80 portions of said body. At least one of these cap portions is made removable from the body of the drum in order to permit the spools of cord to be slipped on to the shaft 2. These cap members, as shown in Fig. 1, 85 are made long enough so as to extend over the end portions of the spool A, and thus form guards to prevent the cord from winding off of the ends of the spool on to the end portions of the shaft. The slots 11 are 90 also made with curved walls so as to be widest at their central portion, and thereby give a constant tendency to the cord passing out through any one of them to be guided toward the center. By the provision of 95 these two features, it is impossible for the cord to wind off from the ends of the spool.

13 is a flanged end disk seated within one end of the body of the drum to rotate therewith.

100 14 is a piece of spring wire which is secured at one end to the shaft 2, its opposite end portion being coiled around a stud or projection 15, on the end disk 13, the free end of the wire bearing against the inner 105 periphery of the drum, as shown at 16. The

free end of the wire 14 is connected by a flexible member, such as a chain 17, with the shaft 2. The connection of this chain with the shaft may be conveniently effected by attaching it to the projecting end of a stop arm 18, which projects radially from the shaft.

In use, the free end of the cord is drawn out through any one of the openings 11 and 10 is partially wrapped around the periphery of the drum 10, with its end hanging in convenient position. When it is desired to draw off a portion of the cord for use, this free end is pulled, thereby unwinding the 15 cord from the spool A. The pull on the cord effects a rotation of the drum 10, causing the chain 17 to wind on the end of the shaft 2, and putting the spring 14 under tension. Fig. 2 shows the normal position 20 of these parts, while Fig. 3 shows the position after the spring has been placed under tension. The drum is prevented from making more than slightly less than one complete revolution by means of the engagement 25 of the stop arm 18 with the stud or projection 15. As soon as the cord is released by the user, the spring 14 at once acts to turn the drum in the opposite direction, and thus wind the excess cord upon the 30 periphery thereof, a length of cord being wound thereon substantially equal to twice the perimeter of the cylinder.

In twine holders previously in use with which we are familiar, and which have been 35 provided with winding means for taking up excess cord, such means fail to operate after the major portion of the cord has been unwound from the spool. This is because of the fact that as the spool of cord becomes 40 smaller and lighter, it does not offer sufficient resistance to cause the pull on the cord to operate the winding spring or weight, but the spool rotates freely on the shaft of the holder. This would not occur if the 45 quills upon which the cord is wound were closely fitted to the shaft, so as to have a considerable frictional engagement therewith. In practice, however, these quills vary considerably in their inner diameters 50 and can not be depended upon to fit the shaft closely. We overcome this objection by providing the shaft 2 with a spring friction member, such as indicated at 19, in Fig. 5. This member may consist of a piece of 55 spring wire having one end secured in the shaft with its free end portion projecting beyond the periphery of the shaft. When the quill is slipped on the shaft, it causes this member to be slightly compressed back 60 into the recess 20 in the shaft. In this manner, the member is caused to have a positive frictional engagement with the inner surface of the quill B. This frictional engagement is sufficient to hold the spool from turning 65 on the shaft except by a sufficient pull

on the cord to effect the rotation of the drum 10. Consequently, no matter to what extent the cord may have been unwound from the spool, sufficient resistance is given the spool to enable the pull on the cord to rotate the 70 drum 10 and put the string 14 under tension. The actual use of twine holders constructed in accordance with our invention has demonstrated that the excess cord may be wound up so long as even a very few 75 turns remain on a spool.

The advantages of our invention will be apparent from the foregoing. The holder is extremely simple in construction and can be manufactured and sold at a comparatively small cost, and the device is extremely efficient in its operation.

We claim:

1. A twine holder comprising a spool carrying shaft, a support in which the shaft 85 is removably seated and having means for holding the shaft against rotation, and a drum mounted to rotate on said shaft and to inclose a spool of twine or cord, said drum having cylindrical end portions of 90 sufficient length to extend over the end portions of the spool, and the drum intermediate of said end portions having openings shorter than the length of said spool and having curved walls arranged to direct the 95 cord toward the central portion of the spool, one of said heads being removable; substantially as described.

2. A twine holder comprising a spool carrying shaft held against rotation, a winding drum mounted to rotate about the axis of said shaft, and spring means for actuating said drum, said means comprising a piece of spring wire secured to the drum at its intermediate portion with one of its free 105 end portions bearing against the inner surface of the drum and its other free end portion extending in the opposite direction within the drum, and a flexible member connecting the last named free end portion with 110 said shaft and adapted to be wound upon the shaft as the drum is rotated; substantially as described.

3. A twine holder having a rotary winding drum, a spool-carrying shaft on which the drum is mounted to rotate, a piece of spring wire secured to the drum at one end, said wire being of a length less than the diameter of the drum, a flexible member connecting the free end of said wire with the 120 shaft and adapted to be wound upon the shaft, and a stop arm for limiting the rotation of the drum, substantially as described.

4. A twine holder comprising a spool-carrying shaft, a support in which the shaft 125 is removably seated and having means for holding the shaft against rotation, a drum mounted to rotate on said shaft and to inclose a spool of twine or cord, said shaft having means for frictionally engaging the 130

interior of the spool for the purpose of increasing its resistance to rotation on said shaft, said drum having end heads, one of which is removable, and the drum having 5 openings intermediate of said heads, and a winding spring arranged within one of said heads, and operatively connected with the drum, substantially as described.

In testimony whereof, we have hereunto set our hands.

ALEXANDER M. KELLY.
BENTON L. SHANER.
